UNITED STATES PATENT OFFICE

CALVIN N. PAYNE, OF TITUSVILLE, PENNSYLVANIA.

SPEED DEVICE.

No. 839,416.

Specification of Letters Patent.

Patented Dec. 25, 1906.

Application filed December 1, 1904. Serial No. 235,103.

To all whom it may concern:

Be it known that I, CALVIN N. PAYNE, a citizen of the United States, residing at Titusville, in the county of Crawford and State of Pennsylvania, have invented new and useful Improvements in Speed Devices, of which the following is a specification.

This invention relates to speed devices; and it consists in certain improvements in the construction thereof, as will be hereinafter fully described, and pointed out in the claims.

The invention is particularly adapted to speed-changing devices used with automobiles and as shown is designed particularly for this use.

Among the important features of the invention are devices through which various speeds may be brought into action by the continuous movement of the controlling mechanism in one direction. In other words, it is not necessary to bring the controlling mechanism to a neutral point to arrange the mechanism for the various speeds. The mechanism for each speed may be coupled up or released by the movement of the controlling mechanism either to the next higher speed or next lower speed, and the movement of the controlling mechanism in either direction releases the mechanism just previously in action.

The other features of the invention will appear from the following description of the claims.

The invention is illustrated in the accompanying drawings, as follows: Figure 1 shows a side elevation of the device; Fig. 2, a view from the opposite side of the device; Fig. 3, a section on the line 3 3 in Figs. 1 and 2; Fig. 4, a section on the line 4 4 in Fig. 3, a part being broken away and in section to better show construction; Fig. 5, a section on the line 5 5 in Fig. 3; Fig. 6, a detail of the controlling mechanism; Fig. 7, a section of said mechanism on the line 7 7 in Fig. 8; Fig. 8, a section on the line 8 8 in Fig. 6.

A marks the drive-shaft, and B the driven shaft. The driven shaft has the sleeved end B', which overlaps the driving-shaft A. The shaft A is mounted in the bearing n², supported on the post N⁴, extending from the base N of the case. The other end of the shaft A is carried in the sleeve end B', and the sleeve B' is carried by the bearing n³, the bearing n³ being supported by the post N⁵,

extending from the base N. The shaft B is also carried by the bearing n⁴, supported by the post N⁶, this post also extending from the base N.

The drive-sleeve C is journaled on the drive-shaft A. It is provided with the ball-openings c, in which are arranged the clutch-balls c'. The shaft A is provided with clutch-slots a, into which the balls c' may be forced for locking the sleeve C with the shaft A. The mechanism for accomplishing this comprises the strap I, cam i³, and lip i⁴, the lip i⁴ being so formed as to prevent the movement of the balls out of the openings c, but to permit a sufficient movement of the balls to clear the shaft A, so as to release the clutch. The strap I is provided with a circumferential groove i, in which the pins i² are arranged. These pins are carried by the rock-arms I'. The rock-arms I' are carried by the shaft I². (See Fig. 5.) The shaft I² is carried by the posts N², extending from the base N. A rock-lever I⁴ extends from the end of the shaft, and the pin I⁵ of this rock-lever extends into a cam-slot P', arranged in the cam-plate P. The cam-plate P is mounted on the face of the gear O². This gear is carried by the bearing n, and the bearing n is supported by the post N⁷, extending from the base N. A rack O' is slidably mounted in the uprights N⁷, extending from said base. The shank O of this rack is connected to the cross-head J'. The cross-head J' is secured to the operating-lever K. When the lever K is at the neutral point, the pin I⁵ is at the point p in the cam-slot. (See Fig. 1.) As this lever is moved forward, the rack operating upon the gear O² moves the cam-plate and the cam-slot, so as to bring the pin I⁵ into the part p' of the cam-slot. This compels a movement of the rock-lever I⁴ and a consequent movement of the strap I, so as to press the balls through the action on the cam i³ and set the clutch.

A series of gears D, D', D², and D³ are fixed on the drive-sleeve C. A reverse-gear D⁴ is also fixed on this sleeve and meshes the intermediate gear D⁵.

A transmission-shaft F is mounted in the bearing n' n', supported by the posts N⁸ N⁹, extending from the plate N. This shaft is hollow and has mounted upon it the gears E, E', E², and E³, meshing, respectively, the gears D, D', D², and D³. It has also the reverse-gear E⁴, meshing the intermediate gear D⁵, it being driven by the gear D⁴. The

gears E, E', E², E³, and E⁴ are provided with the clutch-slots e, e', e², e³, and e⁴, respectively. The ball-openings f, f', f², f³, and f⁴ are cut through the hollow shaft F in the paths of the slots e, e', e², e³, and e⁴, respectively, and these openings are provided with the clutch-balls f⁵, f⁶, f⁷, f⁸, and f⁹, respectively. When these clutch-balls are forced out into the clutch-slots they lock the gear into which they are forced with the transmission-shaft. When, however, the balls are allowed to recede in the ball-openings out of the clutch-slots in the gears, the gears are free to turn on the shaft, the gears being loose thereon. In the operation of the device, therefore, only the gear giving a desired speed is locked with the transmission-shaft. All the other gears, while they remain in mesh, turn freely on said shaft.

20 A controlling device is arranged in the hollow shaft F and is adapted to force the balls into the clutch-slots. It comprises the rod J. This is secured to the cross-head J' by means of the nut j. The rod J has the longitudinal groove j'. This groove is of sufficient depth to permit the balls in register with the groove to move through the ball-openings a sufficient distance to bring them out of the path of the gears, or, in other words, to release the gears from the shaft. The rod J is locked against axial movement by the key j³, which is arranged in the inner part of the shaft and projects into the grooves j² in the rod, so that the groove is at all times in register circumferentially with the balls. A ball-actuating device j⁴ is journaled on the pin j⁹, extending from the end of the rod J. This ball-actuating device has the groove j⁵, which corresponds to the groove j' when brought into line therewith. The front end of the ball-actuating device j¹² is beveled so that as the rod J, and with it the ball-actuating device, is moved through the shaft this surface j¹² engages the balls and forces them up through the openings in the clutch-slots to set the clutch. Ordinarily the device would be started at the neutral point and would first pick up the low-speed gear E and then the gears of the higher speed-gears E', E², and E³, successively. The ball-actuating device is not of sufficient length to hold more than one set of balls in engagement at one time, and as it passes from under the balls they drop into the groove j', thus releasing the clutch from the gear just previously locked with the transmission-shaft. It may also be moved from the neutral point to the reverse gear E⁴. Here the opposite end of the ball-actuating device engages the ball; but it is so shaped as to effect this result. It may happen in the operation of an automobile and of other machinery to which this may be applied that the machine is stopped with the clutch set in the high gear. It is desirable to be able to

bring the controlling mechanism to the neutral point and to release the clutch from the high gear before starting the machine. I therefore mount the ball-actuating device rotatively and provide it with the grooves j⁵ and cam-surfaces j⁶. The cam-surfaces contacting the balls which are held to the inner position by the inner surfaces of the gears turn the ball-actuating device on the pin j⁹, so as to bring the groove j⁵ into register with the groove j', and thus permit the passage of the ball-actuating device past the balls.

Any convenient mechanism may be used for normally holding the actuating device in position to force the balls into clutch relation. I have, however, arranged the following mechanism: The front end of the ball-actuating device is provided with the cam j⁷, which engages a cam j¹³ on a cam-block j⁸. The cam-block is mounted on the pin j⁹, but is locked against rotative movement by the pin j¹⁰, which extends into the cam-block and slidingly into the openings j¹⁴ in the end of the extension J². Springs j¹¹ are mounted in the openings j¹⁴ so as to press against the pins j¹⁰. As the ball-actuating device j⁴ is turned through the action of the cam-surfaces j⁶ on the balls the cam-surface j⁷ acting against the cam-block j⁸ forces the cam-block against the spring. As soon as the ball-actuating device passes by the balls the springs acting on the block j⁸ through the action of the cams j⁷ and j¹³ force the ball-actuating device back to its normal position. It will be noted that the ball-actuating device may be moved immediately to position, to throw any of the transmission-gears into engagement even though the ball and socket of this gear is not for the moment in register, and when this happens the ball-actuating device will be turned against the tension of the spring, so that when the ball-socket and ball-opening come into register the ball-actuating device acting under the influence of the spring turns and the slanting edges of the sleeve force the balls into engagement.

The transmission-shaft has fixed on its end a gear G, which meshes with the gear H. This gear H has a sleeve-like hub h, in which are ball-openings h'. Balls h² are arranged in these ball-openings. The shaft B is provided with the clutch-slots b, into which the balls are forced to lock the shaft B with the sleeve h. A strap L is mounted on the sleeve. It has the cam-surface l arranged to force the balls into the clutch-slots b with an axial movement of the strap and the lips l' for preventing the escape of the balls from the opening. The strap L is provided with the circumferential groove l², in which are arranged the pins l³. These pins are secured in the rock-arms L'. These rock-arms are mounted on a shaft L², and this shaft is mounted in the projections N⁸ in the plate

- N. A link M engages the pins l^3 and l^2 , and thus connects the straps I and L. A spring L³ is tensioned against a projection l^4 and a shoulder l^5 on a pin L⁴. The end of the pin L⁴ is secured to one of the pins l^6 , and the spring is tensioned so as to force the strap forward to set the clutch through the action of the balls h^2 . The link M where it engages the pin i^5 has the slot m , which permits some play. When, therefore, the lever K is operated so as to force the strap I forward and set the clutch with the ball c' , it also moves the pin i^2 in the slot n and permits the spring L³ to force the strap L forward to set the clutch with the balls h^2 . If the link M were positively connected to the strap, or, in other words, if the strap were not provided with the slot m the balls h^2 , which are then in the stationary driven shaft B, may be in such position as to prevent the immediate forward movement of the strap. It becomes necessary, therefore, to provide mechanism whereby the clutch with the driving-shaft may be set and the setting of the clutch with the driven shaft follows as soon as slot b is brought under one of the ball-openings h' . It is desirable in order to add to the variety of speeds that may be attained to be able to connect the driving and driven shafts directly. I have arranged a mechanism whereby this may be accomplished through the action of the same controlling-lever K by moving continuously that lever in the direction it has been moved to bring into action the higher speeds. The driving-shaft A is provided with the clutch-slots a' . These are in the path of the ball-openings b' in the extension B'. The balls b^2 are arranged in the openings b' and are in the path of the cam-surfaces b^3 on the strap I. The lips b^4 prevent the escape of the balls from the opening, but are of such size as to permit of the outward movement of the balls so as to disengage them from the driving-shaft. When the lever K has been moved forward so as to bring the pin I⁵ at the end of the part p' of the slot P, the ball-actuating device j^4 has passed beyond the balls f^8 , or beyond the highest-speed gear. A further movement of the lever moves the rock-arm I⁴, and with it the strap I and L, so as to release the clutches formed by the balls c' and h^2 . A further movement of the lever through the action of the part p^2 of the cam-slot moves the arm I⁴, so as to bring the strap I to a position to force the balls b^2 into engagement of the clutch-slots a' . This locks the shaft A directly with the extension B', and consequently with the driven shaft. At the same time the transmission-gear has been thrown out both by the clutch formed with the openings h' and the clutch formed with the openings c' . As the lever is returned to the neutral point the clutch between the driving and driven shaft is first released. Then the clutch formed by the balls h^2 and c' is thrown in, and the high-speed gear is picked up and the lower-speed gears in succession. The only purpose of providing the neutral point p is to save the wear on the gears. Simply bringing the ball-actuating device j^4 to a position between the gears E and E⁴ would stop the driving action of the device; but the movement of the lever K not only brings the ball-actuating device j^4 to that position, but also brings the part p of the cam-slot into action to throw out the clutch between the driving-sleeve C and the driving-shaft, so that the only wear is between the driving-sleeve and driving-shaft. If it is desired to have a reverse movement of the device, the lever is thrown still further in the backward direction, bringing into action the part p^3 of the cam-slot P, which throws the lever I⁴, so as to throw in the clutch between the driving-shaft and driving-sleeve C, and this movement of the lever also brings the ball-actuating device j^4 under the ball e^4 , so as to lock the reverse-gear with the transmission-shaft.
- What I claim as new is—
1. In a speed-changing device, the combination of the driving-shaft and driven shaft, arranged in alinement, a transmission-shaft parallel thereto, means for transmitting the movement from one of the alined shafts to the other through the transmission-shaft with at least three speeds in the same direction, devices for disconnecting said means, and mechanism independent of said means for connecting the driving and driven shafts directly together.
  2. In a speed-changing device the combination of a driving-shaft; a driven shaft in alinement with the driving-shaft; a transmission-shaft; a plurality of gears on one of the alined shafts of different sizes; a clutch for locking said gears with said alined shaft on which the gears are mounted; a series of gears on the transmission-shaft in mesh with the gears on the alined shaft and arranged to transmit at least two different speeds in the same direction; a gear connection between the transmission-shaft and the other of the alined shafts; a clutch between the driving and driven shafts; and means for throwing out the clutch between the gears on the alined shaft and said shaft when the driving-shaft is locked directly with the driven shaft.
  3. In a speed-changing device the combination of the driving-shaft; a transmission-shaft; a driven shaft in alinement with the driving-shaft; a series of at least three gears on the transmission-shaft; a similar series of gears on one of the alined shafts, said gears being arranged to give at least three speeds in one direction; a clutch for locking said gears on the said alined shaft with said shaft; a gear connection between the transmission-

shaft and the other alined shafts; a clutch between the driving-shaft and driven shaft; and means for throwing out the clutch between the series of gears on the alined shaft and said shaft when the driving-shaft is locked directly with the driven shaft.

4. In a speed-changing device, the combination of the driving-shaft; a transmission-shaft; a series of at least three gears on the driving-shaft of different sizes; a clutch for locking said gears with said driving-shaft; a series of at least three gears on the transmission-shaft meshing with the gears on the driving-shaft, said gears being arranged to give to the transmission-shaft at least three different speeds with a given speed of the driving-shaft; a driven shaft in alinement with the driving-shaft; gears for transmitting the motion of the transmission-shaft to the driven shaft; a clutch between the driving-shaft and driven shaft; and means for throwing out the clutch between the driving-shaft and the gears upon said shaft when the driving-shaft is locked directly with the driven shaft.

5. In a speed-changing device, the combination of the driving-shaft; a transmission-shaft; one of said shafts being hollow and having ball-openings therein; balls arranged in said openings; a series of gears on the shaft having said openings, said gears having clutch-sockets therein arranged in the path of the ball-opening; a ball-actuating device in the hollow shaft, said ball-actuating device being rotatively mounted and arranged when in one position to force the balls into clutch position and when turned to another position, to move past the balls with the speed-changing device stationary; and gears on the other of said shafts.

6. In a speed-changing device, the combination of the driving-shaft; a transmission-shaft, one of said shafts being hollow and having ball-openings therein; balls arranged in said openings; a series of gears on the shaft having said openings, said gears having clutch-sockets therein arranged in the path of the balls in said openings; a ball-actuating device in the hollow shaft, said ball-actuating device being rotatively mounted and arranged when in one position to force the balls into clutch position and when turned to another position, to move past the balls with the speed-changing device stationary; and gears on the other of said shafts.

7. In a speed-changing device, the combination of the driving-shaft; a transmission-shaft parallel to the driving-shaft; one of said shafts being hollow and having ball-openings therein; balls arranged in said openings; a series of gears on the shaft having said openings, said gears having clutch-sockets therein arranged in the path of the balls in said openings; a ball-actuating device in the hollow shaft, said ball-actuating device being rota-

tively mounted and arranged when in one position to force the balls into clutch position and when turned to another position to move past the balls with the speed-changing device stationary; and gears on the other of said shafts.

8. In a speed-changing device the combination of two shafts, one of which is hollow and provided with ball-openings; a series of gears on said hollow shaft; balls in said openings adapted to lock the gears with the shaft; a ball-actuating device in the hollow shaft, said ball-actuating device being spring-actuated and arranged to move to its position independently of a movement of the balls and to force the balls to engagement when the parts assume position permitting said engagement; and said spring.

9. In a speed-changing device the combination of two shafts; means for communicating movement from one shaft to the other at different speeds; comprising a ball-clutch, one element of the clutch having a ball-opening the other element a socket and comprising a ball arranged in the opening and adapted to be forced into the socket when the opening and socket are in register to lock the clutch; a controlling device for throwing said clutch into engagement comprising a yielding spring mechanism arranged to permit the controlling device to be moved to position to throw the clutch into engagement with the opening and the socket out of register and to throw the clutch into engagement through the action of the spring mechanism when the socket and ball come into register.

10. In a speed-changing device, the combination of the drive-shaft; a transmission-shaft, one of said shafts being hollow and having ball-openings therein; balls arranged in said openings; a series of gears on each of said shafts and in mesh, the gears on the hollow shaft having clutch-sockets in the path of the balls in the ball-openings; controlling mechanism comprising the rod J of a cross dimension to allow the balls to pass out of action, and the ball-actuating device j^4 having the groove j^5 adapted to be brought into register with the balls by a rotative action of the ball-actuating device and having also the cam-surface j^6 for rotating same for action on the balls, and a mechanism for returning the ball-actuating device to normal after the passage by a ball.

11. In a speed-changing device, the combination of the drive-shaft; a transmission-shaft, one of said shafts being hollow and having ball-openings therein; balls arranged in said openings; a series of gears on each of said shafts and in mesh, the gears on the hollow shaft having clutch-sockets in the path of the balls in the ball-openings; and a controlling mechanism comprising the rod J, the ball-actuating device j^4 having the groove j^6

normally out of line with the ball and the cam-surface j^6 for rotating the ball-actuating device, the ball-actuating device having the cam j^7 , the cam-block j^8 having also the cam-surface j^9 for acting upon the actuating device, and springs tensioned to exert pressure upon the cam-block.

12. In a speed-changing device the combination of a driving-shaft; a transmission-shaft; a driven shaft in alinement with the driving-shaft; a series of gears on one of the alined shafts and the transmission-shaft of different sizes adapted to communicate movement from said alined shaft to the transmission-shaft; a gear connection between the transmission-shaft and the other alined shaft; means for throwing the gears of the transmission-shaft successively into engagement with the transmission-shaft by a movement of the controlling mechanism in one direction; a clutch between the driving and driven shafts; and means for operating said clutch to throw it into action by a movement of the controlling mechanism past a point throwing in the highest-speed gear.

13. In a speed-changing device, the combination of the drive-shaft; a transmission-shaft; a driven shaft; a series of gears on the drive and transmission shafts of different sizes and adapted to communicate movement from the drive-shaft to the transmission-shaft; means for communicating movement of the transmission-shaft to the driven shaft; means for throwing the gears of the transmission-shaft successively into engagement with the transmission-shaft by a movement of the controlling mechanism in one direction; a clutch between the driving and driven shaft; and means for operating said clutch to throw it into action by a movement of the controlling mechanism past a point throwing in the highest-speed gear.

14. In a speed-changing device the combination of a driving-shaft; a transmission-shaft; a driven shaft in alinement with the driving-shaft; a series of gears on the transmission-shaft; a series of gears on one of the alined shafts continuously in mesh with the series of gears on the transmission-shaft; a controlling mechanism for throwing said gears on the transmission-shaft into and out of engagement therewith; a gear connection between the transmission-shaft and the other of the alined shafts; a clutch between the driving and driven shafts; and means for actuating said controlling mechanism and said clutch between the driving and driven shafts, arranged to throw in the clutch between the driving or driven shafts after the controlling mechanism has thrown into and out of engagement the highest-speed gear on the transmission-shaft and by a continuation of the movement of said means in a direction toward which it is moved to move the con-

trolling mechanism from the low-speed gear 6¹ to the high-speed gear.

15. In a speed-changing device, the combination of a drive-shaft; a transmission-shaft; a series of gears on said shafts continuously in mesh; a controlling mechanism for throwing said gears on one of said shafts successively into and out of engagement with the shaft on which they are mounted; a driven shaft; means for transmitting the movement of the transmission-shaft to the driven shaft; a clutch between the driving and driven shafts; and means for actuating said controlling mechanism and said clutch between the driving and driven shaft arranged to throw in the clutch between the driving and driven shaft after the controlling mechanism has thrown into and out of engagement the highest-speed gear on the transmission-shaft and by a continuation of the movement of said means in the direction toward which it is moved to move the controlling mechanism from the low-speed gear to the high-speed gear.

16. In a speed-changing device the combination of a driving-shaft; a transmission-shaft; a driven shaft in alinement with the driving-shaft; a sleeve on one of said alined shafts; a series of gears fixed on said sleeve; a series of gears on the transmission-shaft in mesh with the gears on said sleeve; a clutch between the sleeve and the shaft on which it is mounted; a gear connection between the transmission-shaft and the other alined shaft; a clutch controlling said connection; and means for throwing said clutch controlling said connection into and out of engagement and said gears into and out of action by a continuous movement of said means to effect first—the low speed, then successively the higher speeds through the transmission-shaft, then to throw out the transmission-shaft and couple the driving-shaft directly with the driven shaft through said clutch between said driving and driven shafts.

17. In a speed-changing device, the combination of a driving-shaft; a driving-sleeve on said shaft; a series of gears mounted on said sleeve; a clutch between the driving-shaft and the sleeve; a transmission-shaft; a series of gears on the transmission-shaft arranged in mesh with the gears on the driving-sleeve; a driven shaft; gears connecting the transmission-shaft with the driven shaft; a clutch controlling said connection; devices compelling the action of the clutch controlling said connection and the clutch between the driving-shaft and driving-sleeve to operate in unison; a clutch between the driving and driven shafts; and means for throwing said clutches into and out of engagement, and said gears into and out of driving action by a continuous movement of said means to effect first the low speed, then successively the

higher speeds through the transmission-shaft, and then to throw out the transmission-shaft and couple the driving-shaft directly with the driven shaft through said clutch between said driving and driven shafts.

18. In a speed-changing device the combination of a driving-shaft; a transmission-shaft; a driven shaft in alinement with the driving-shaft; a series of different-sized gears on one of said alined shafts; corresponding gears on the transmission-shaft; a gear connection between the transmission-shaft and the other of said alined shafts; a clutch between the driving and driven shafts; a clutch between the gear on the alined shaft and said shaft; a cam and mechanism actuated by said cam for operating and timing the operation of both clutches; and devices for actuating said cam.

19. In a speed-changing device, the combination of a driving-shaft; a transmission-shaft; a driven shaft; a series of speed-gears on the driving and transmission shafts; means for communicating the movement of the transmission-shaft to the driven shaft; a clutch between the driving-gears and the drive-shaft; a clutch between said driven shaft and said means; the cam-plate P having the cam-slot therein; mechanism actuated by said cam for throwing said clutches into and out of action in unison; devices for actuating said cam; a clutch for coupling the drive and driven shafts directly; devices carried by said mechanism for actuating said clutch, said mechanism being timed to throw the clutch between the drive-gear and drive-shaft and the clutch between said means and driven shaft out of action before throwing into action the clutch between the drive-shaft and driven shaft.

20. In a speed-changing device, the combination of a driving-shaft having the slot a therein; the sleeve C on the driving-shaft having the opening c therein; drive-gears on said sleeve; a transmission - shaft; gears mounted on said transmission-shaft in mesh with the gears on said sleeve; the driven shaft B having the ball-slot b therein; a connecting-gear on the transmission-shaft; a gear on the driven shaft having a ball-opening h' therein; a clutch between the driving-shaft and sleeve C comprising the ball c' arranged in the opening c in the sleeve C and adapted to be forced into the slot a in the drive-shaft; the strap I for engaging said ball and forcing it into action; the rock-arm I' controlling the movement of said strap; the rock-arm I⁴ controlling the movement of the rock-arm I'; the cam P having the cam-slot therein for actuating the lever I⁴; the gear O² connected with said cam-plate; a rack for actuating said gear; a clutch comprising the ball h' arranged in the ball-opening h' and adapted to be forced into the slot b in the driven shaft; the

strap L for forcing said ball through the opening into said slot; and a connection between the strap L and strap I to effect the engagement and disengagement of said clutches in unison.

21. In a speed-changing device, the combination of a driving-shaft having the slots a and a' therein; the sleeve C on the driving-shaft having the opening c therein; the drive-gears on said sleeve; a transmission-shaft; gears mounted on said transmission-shaft and in mesh with the gears on said sleeve; the driven shaft B having the ball-socket b therein; a connecting-gear on said transmission-shaft; a gear on the driven shaft B in mesh with said connecting-gear, said gear on the driven shaft having a ball-opening h' therein; a clutch between the driving-shaft and sleeve C comprising the ball c' arranged in the sleeve C and adapted to be thrown into the slot a in the driving-shaft; the strap I for engaging said ball and forcing it into action; the arm I' controlling the movement of the strap; the rock-arm I⁴ controlling the movement of the rock-arm I'; the cam-plate P having the cam-slot therein for actuating the rock-lever I⁴; the gear O² connected with said cam-plate; the rack for actuating said gear; a clutch comprising the ball h' arranged in the ball-opening h' for locking the gear on the driven shaft with said shaft; the strap L for forcing said ball through the opening h' into engagement; a connection between the strap L and strap I to effect the engagement and disengagement of said clutches successively; a clutch comprising the extension b' having the ball-opening b' therein; the ball-actuating cam b³ on the strap I adapted to force the ball in the opening b' into the clutch-slot a' in the drive-shaft for locking the drive-shaft directly with the driven shaft; the strap I being proportioned to release the clutch between the driven-shaft and sleeve C before the setting of the clutch between the driving and driven shafts.

22. In a speed-changing device, the combination of a driving-shaft; a sleeve C on the driving-shaft; drive-gears on said sleeve; transmission-shaft; gears mounted on said transmission-shaft; the driven shaft B; gears connecting the transmission - shaft with the driven shaft; the clutch between the driving-shaft A and sleeve C, comprising balls c' arranged in the openings c in the sleeve C and adapted to be thrown into the slots a in the shaft A; the strap I for engaging said balls and forcing them into action; the rock-arms I' controlling the movement of said straps; the rock-arm I⁴ controlling the movement of the rock-arms I'; the cam-plate P having the cam-slot therein for actuating the rock-lever I⁴; the gear O² connected with said cam-plate and the rack for actuating said gear.

23. In a speed-changing device the com-

bination of two shafts parallel to each other; a series of gears on each of said shafts; a clutch between one of said shafts and the gears thereon; means for throwing the gears on the other of said shafts into and out of driving action successively; and means for releasing said clutch at a point where all the gears on said other shaft are thrown out of driving action.

10 24. In a speed-changing device, the combination of a driving-shaft; a transmission-shaft; a series of gears on each of said shafts; a clutch between the driving-gears and the driving-shaft; means for throwing said gears on the transmission-shaft into and out of action successively; and means for throwing out the clutch between the driving-shaft and driving-gears at a point where all the gears on the transmission-shaft are thrown out of 20 action.

25. In a speed-changing device, the combination of a shaft A; the sleeve C thereon; a clutch between the sleeve and shaft A; a series of gears on the sleeve; a transmission-shaft; a series of gears mounted on said shaft and in mesh with the gears on the shaft A; controlling mechanism for throwing said gears on the transmission-shaft into and out of engagement with said shaft; and means 30 connected with said controlling mechanism for throwing said clutch between the sleeve C and shaft A out of action when the controlling mechanism has thrown out of engagement the gears on the transmission-shaft.

35 26. In a speed-changing device, the combination of the shaft A; the drive-sleeve C; a series of gears on said drive-sleeve; the gear D⁴ on said sleeve; a transmission-shaft; a series of gears on said shaft in mesh with the 40 gears on the sleeve C; the reverse-gear E⁴ on the transmission-shaft; an intermediate gear meshing with the gear E⁴ and D⁴; controlling mechanism for throwing said gears successively into and out of engagement; a clutch 45 between the drive sleeve and shaft A; means connected with said controlling mechanism for actuating said clutch to throw it out of engagement when the controlling mechanism is at a point between the reverse-gear and the 50 adjacent gear of the series on said transmission-shaft.

27. In a speed-changing device, the combination of the shaft A; the drive-sleeve C; a series of gears on said drive-sleeve; the gear D⁴ on said sleeve; a transmission-shaft; a series of gears on said shaft in mesh with the gears on the sleeve C; the reverse-gear E⁴ on the transmission-shaft; an intermediate gear meshing with the gear E⁴ and D⁴; controlling 55 mechanism for throwing said gears successively into and out of engagement; a clutch between the drive-sleeve and driving-shaft; means connected with said controlling mechanism for actuating said clutch to throw it

out of engagement when the controlling 65 mechanism is at a point between the reverse-gear and the adjacent gear of the series on said transmission-shaft; and means for throwing in said clutch with the movement of the controlling mechanism to throw the reverse-gear into engagement. 70

28. In a speed-changing device, the combination of a shaft A; the sleeve C; a clutch between said sleeve and shaft; a series of drive-gears on the sleeve C; a transmission-shaft; a series of gears on said shaft meshing with the gears on the sleeve; the reversing-gear D⁴ on the sleeve; the reversing-gear E⁴ on the transmission-shaft; an intermediate gear meshing with said gears; the cam-plate P 80 having the cam-slot therein provided with the neutral point p, reverse part p³ and part p'; mechanism controlled by said cam-slot for throwing the clutch between the driving-shaft and sleeve C into engagement as the 85 parts p' or p³ are brought to a certain point; a controlling mechanism for throwing said gears on the transmission-shaft successively into engagement with said shaft; devices for actuating said cam-plate and controlling mechanism together; and devices to bring the active part of the cam-slot p to the neutral point and to throw out the clutch between the driving-shaft and drive-sleeve with a controlling mechanism between the reversing-gear E⁴ and the adjacent gear on the transmission-shaft. 95

29. In a speed-changing device, the combination of a shaft A; the sleeve C; a clutch between said sleeve and shaft; a series of drive-gears on the sleeve C; a transmission-shaft; a series of gears on said shaft meshing with the gears on the sleeve; the reversing-gear D⁴ on the sleeve; the reversing-gear E⁴ on the transmission-shaft; an intermediate gear meshing with said reversing-gears; the cam-plate P having the cam-slot therein provided with the neutral point p, reverse part p³ and part p'; mechanism controlled by said cam-slot for throwing the clutch between the driving-shaft and sleeve C into engagement as the parts p' or p³ are brought to a certain point; a controlling mechanism for throwing said gears successively into engagement; devices for actuating said cam-plate and said controlling mechanism together; and devices to bring the active part of the cam-slot p to the neutral point and to throw out the clutch between the driving-shaft and drive-sleeve with a controlling mechanism between the reversing-gear E⁴ and the adjacent gear on the transmission-shaft; a clutch directly between the driving and driven shaft, said clutch being operated by the part p² of the cam-slot and at a time when the controlling mechanism has put into engagement and out of engagement all the drive-gears on the transmission-shafts. 115 120 125

30. In a speed-changing device the combination of a transmission-shaft; a driving and driven shaft in alinement with each other; a series of gears on the transmission-shaft; a series of gears on one of the alined shafts in mesh with the gears on the transmission-shaft; a ball-clutch for locking said gears on the alined shaft with said shaft; a gear connection between the transmission-shaft and the other alined shaft; a ball-clutch for locking said alined shafts together; and a collar

I having the cams thereon for actuating both of said clutches and so spaced as to release one of said clutches before operating the other.

In testimony whereof I have hereunto set my hand in the presence of two subscribing witnesses.

CALVIN M. PAYNE.
